SEPARATOR SYSTEM

Application filed November 20, 1925. Serial No. 70,386.

My invention relates to separator systems, and more particularly to systems for separating solid matter from gases.

In the field of the industrial arts, a problem of ever increasing importance is that of separating matter, usually in the form of dust, from gases emitted by chimneys or released by refining or other manufacturing processes. The existence of this problem may be said to be due to two major reasons; first, the pollution or contamination of the air in a community or of the air in an agricultural district; and second, to uneconomic conditions where valuable materials may be allowed to escape and thereby wasted.

It is well established that in the administration of a community or district, rigid measures may be prescribed and enforced as to the content or character of the gases which may be released by a plant. Such restrictive measures grow and become more exacting with the ever increasing size of industrial plants, increase of population in communities, and with the growth of activity in agricultural sections.

In the art concerned, the more strict repressive measures and greater potential values in waste materials have, in a large measure, been responsible for establishing that the majority of the former processes are inadequate to cope with the existing conditions, and that in attempting to apply other proposals the results have been disappointing or the costs have been prohibitive.

The matter which forms the dust content of laden gases may range in character from relatively heavy particles of appreciable size to particles of microscopic size and inappreciable weight. In the art, these particles are referred to in general terms as "heavies" and "fines", respectively. Ordinarily, least difficulty is had in separating and removing the heavy particles. Heretofore, however, the handling of the finer particles has been a perplexing problem, the difficulties increasing rapidly with the degree of refinement or percentage of dust sought to be removed.

A phenomenon frequently encountered, particularly when dealing with gases at high temperatures, is that the dust content ex-

hibits so-called "live" characteristics. In this condition the dust shows little tendency to settle, and under but slight movement of the suspending gases may continue to "float" for long periods. This is usually due to electrification effects. Conducting particles may become directly charged due to an ionized condition of the gases, and some of the ions may also attach to the non-conducting particles. In such a state the different particles are charged in a like polarity sense, and due to mutual repulsion, show substantially no tendency to coalesce and settle, with the result that a large percentage of the finer particles are carried through a separator apparatus. The importance attaching to removal of the finer dust particles is usually greater than that resting with the removal of the heavier dusts, principally due to the fact that the former may drift or float to greater distances before settling and thus menace or pollute larger areas.

The conditions and difficulties peculiar to one branch of the separator art to which my invention appertains, have been pointed out more for the purpose of general illustration. Therefore, when the foregoing is taken with the description to follow, it will be obvious to those skilled in the art that my system may be readily employed in other situations, as the recovery of dust from the gases of cement kilns, removal of dust from smelting processes and other operations, recovery of sugar in the form of dust from the air of granulators in sugar refineries, and the like.

To the above end, it is the principal object of my invention to provide an improved system for more effectively, reliably, and more economically separating and recovering solid matter from gases, including gases at high temperatures.

Prior systems and proposals have usually been based on such principles as filtration, centrifugation, gravity precipitation in the still areas of large settling chambers, impingement, absorption by means of liquid sprays, and electrical precipitation. Knowledge of these principles coupled with an understanding of the difficulties peculiar to handling the finer dusts, led me to experi-

ments looking to the introduction of a new principle in the separator art. This new principle is based on the phenomena of the vortex, observed in nature and commonly referred to as the atmospheric vortex or whirlwind. These effects are usually due to unequal pressure areas, and in nature appear as vertical columns in which the spiral progression of the gyrating air is along a central axis which may have appreciable longitudinal length in transmitting air from a high pressure area at the surface of the ground to a low pressure area at some upper point. Rarefaction at the axis is generated by the rapidity of the vorticos movement. This results in a strong inflowing current of air at the base which is drawn along and may ascend through the central axis of the column, until dispersed at an upper level. Visual evidence of a whirlwind is due to the fact that the in-curving air currents at the base are charged with fine dust particles which ascend with the air as it is drawn upwards through the center of the vortex. When the dust content is sufficiently dense or the "loading" (grams of dust per cubic foot of air) is relatively heavy an atmospheric vortex may have the appearance of a dust or sand pillar.

The phenomena of vortices differ in important ways from the phenomena of centrifugal action and ordinary eddies, when considering such principles from the standpoint of dust separation. In a vortex the higher velocities are toward the center rather than at the periphery, where the tangential effects are at a maximum under centrifugal action. Therefore, while centrifugation may tend to separate heavier particles of dust from gases, the inappreciable weight of fine dust particles renders them immune to such action and such particles may continue in suspension in the gases. Substantially similar results are had when the principles of impingement are employed, the heavier particles being susceptible to separation from the gases, following impact, while the lighter particles may be unaffected and continue in suspension.

On the assumption that the finer and lighter dust particles will be influenced or drawn to the center of a vortex, while heavier dust particles may be released tangentially from the outer regions of a gyrating column of dust laden gases, I provide a chamber which may be traversed by a stream of gases in such a manner that high pressures will be established in the upper areas while lower pressures may result in the lower areas of the chamber. Receptor members are arranged so that under momentum of the gases, vortices will be set up to connect the upper with the lower areas. After reaching the latter points diffuser members check the gyrating movement of the gases and deflect them along to pressure relief points where they may rise

and again enter the main gas currents through the chamber.

At the diffuser members the dusts continue downward into the dead or still gas spaces of the hopper or dust collecting units. In establishing the different pressure areas for setting up the vortices within the chamber different deflector members are employed in such a manner that vertically extending low pressure areas will be established at rarefaction members. The latter locations constitute the pressure relief points above mentioned. The deflector members also serve as impingement means and effect separation of an appreciable amount of the heavier dust particles. The operations just described are repeated through a series or succession of steps until the gases have been clarified to a desired degree, following which they may pass from the chamber.

In this specification the term "dust" will be understood as applying to any substance which may be reduced to a fine powdery form, while the term "gas" may embrace all matter in an aeriform state, including vapors and fumes.

My invention is illustrated diagrammatically in the accompanying drawings, in which—

Fig. 1 is a plan view of the separator chamber with the top removed to show the arrangement of the internal equipment;

Fig. 2 is a front elevation on the line BB, of the chamber Fig. 1;

Fig. 3 is a side elevation on the line CC, Fig. 1; and

Fig. 4 is an elevation in an isometric projection, on an enlarged scale, to illustrate the internal arrangement of the chamber Fig. 1.

Throughout the various views of the drawings like characters of reference have been employed for indicating similar or like parts.

To those skilled in the art to which my invention appertains, it is believed that a description of a single application of its use will be sufficient to convey a clear understanding of its application and use in other branches and situations of the separator art. Therefore, I will now describe my system in its application to the separation and recovery of dust from the smoke gases which may result from combustion in the boilers of power generating plants, and the like.

Referring to the drawings, let it be assumed that the chamber, Fig. 1, is positioned in a lateral or transverse section of a draft or flue way at a point intermediate a battery of boilers and a chimney or smoke stack (not shown). Dust laden gases may enter at port 1 and after being cleaned or freed from the dust may pass out through a second port 2.

Within the chamber a plurality of ranks or rows, 3, 4, 5, 6, 7, and 8 of variously shaped and vertically positioned members, are placed to form a succession or series of transverse

alignments across the chamber. As shown, the form and arrangement of the members comprising the ranks is typical, one rank with the others. Each rank has two similarly formed receptor members 10 and 11, one at each end, a receptor member 12 at the middle, combined deflector and rarefaction members 13 and 14 placed midway between the central member 12 and the respective end members, while respective groups of deflector members 15, 16, 17, and 18 are fixed at intermediate points in a rank, as shown. As spaced, the members 10 to 18 afford a plurality of free gap-spaces which, for convenience, have been designated as groups 19, 20, 21, and 22.

In association with each of the ranks 3 to 8 is a diffuser plate 25 fixed immediately below the members 10 to 18 and arranged to extend downwardly for a limited distance within the respective hopper or dust compartments 26. As separated by partition members 27 the hopper or dust compartments occupy a lower extension of the separator chamber proper. The relation of the various parts may be more clearly seen in the views, Figs. 3 and 4. In the latter figure, the vertical members 10, 13, and 15 only, of a rank have been shown as the arrangement and relation of these is typical of the arrangement and relation of the other vertical members of a rank. In the latter view, the associated member 25 and partition 27 are also clearly shown in their relation to the other parts. It may be pointed out that the distance to which the diffuser plate 25 may extend downwardly is of some importance, and may therefore be varied in a fixed way for any given situation.

In the operation of this separator, dust laden gases entering the chamber through the port 1, as indicated by the arrows, successively encounter members 10 to 18 of the ranks 3 to 8. This results in the building up of higher pressures in front of the members 10, 11, and 12. As the upper ends of these members are closed by the top shell or cover of the chamber, while the lower ends are open, downward flow of the gases through the length of these members takes place due to the lower pressures at their lower extremities. The flow of the gases through the separator chamber is tangential to the surfaces of the receptor members 10, 11, and 12, and a vortex will be set up at each of the members 10 and 11, while both a right hand vortex and a left hand vortex will be set up before the member 12. Under the downward pressure and travel of the vortices the gases arrive at the diffuser plate 25, where the vortices are broken up and the downward rush of the gases is presently checked by pressure effects against the still or dead gases within the hopper 26. Such of the gases as may then be on the front or "near" side of the plate 25 may be deflected therealong to points of least pressures where they may pass

around this plate in continuing their journey toward the rear of the main chamber. The arrows in Fig. 4 have been placed to show approximately the direction and behavior of the gases under the operations just described. Under the action of these vortices not only are the finer dusts separated from the gases and precipitated to settle within the hopper 26, but a portion of the heavier dust particles is also brought down and caused to settle at the same points. The action with the latter particles appears to be due both to impingement and to centrifugal action, set up by bombardment of the surface of the receptor members 10, 11, and 12 under the vorticoso movement of the gases. As already mentioned, the finer dusts are drawn to the center of the vortices, and irrespective of whether the particles may be under electrification as above described, they are driven downward into the hopper or reclaiming chamber 26.

The plate groups 15, 16, 17, and 18 are set at respective angles so that the inrushing gases on striking the surfaces of these plates, may in passing through the respective groups of gap spaces 19, 20, 21, and 22, be directed to the receptor members 10, 11, and 12, of the next and succeeding ranks 4 to 8. This directive effect may be seen to be progressive relative to concentration of the gases and therefore a building up of higher pressures within the control of these members in the successive ranks.

The inversely faced rarefaction members 13 and 14, aside from affording deflector effects as already described, establish relief or low pressure ways up which the gases may rush following breaking up of the vortices at the plate 25. This equalizing effect may be more readily understood after pointing out that since the two groups of deflector plates 15 and 16 serve to direct the gases respectively to the left and right in building up higher pressures at the members 10 and 12, it results that somewhat lower pressures will exist at the rarefaction side of the member 13. Due to the deflected course of the gases as effected by the plates 15 and 16 a minimum of dust precipitation will be had in the region at the rear of the member 13. Therefore, the rising gases may not become reloaded with dust particles, but under decreasing pressure effects through the chamber, may be drawn into the currents of the main gas streams through the apertures 19 and 20. It will be obvious that what has just been said with respect to the action of the gases in the left-hand side of the chamber may also apply to the action of the gases in the right-hand side, where duplicate equipment is present.

Coincident with the operations already described, at the instant the inrushing gases strike the members of the first rank 3, dust particles, particularly the heavier ones, are

arrested due to impingement. Then, under the effect of gravity these particles are influenced to a downward course which finally leads to the hopper 26. Under repetition of impingement at the successive rows of members 4 to 8 an appreciable precipitation of the heavier particles is had in the successive hopper or reclaiming chambers 26.

By reference to Fig. 4, in which arrows have been placed to approximate the flow and behavior of the gases, a clear understanding of the action of the system may be had. On sweeping into the receptor member 10 the curvature or angular form of this member causes the gases to rotate rapidly in a descending spiral, thus forming a vortex, the longitudinal length or the axis of which may approximately correspond with the length of this member 10. The tendency to rarefaction at the center of this gyrating column of gas results in concentration of the dust content of the gases at this axial center where the strong pull of the existing down draft or suction carries the particles in the direction of gravity toward the hopper 26. The diffuser member 25 is positioned across and substantially central beneath the vertical members to break up and dissipate the vertically moving gases. The dust continues downward through the still gases of the hopper 26 to settle therein, while the dissipated gases will encounter the pressure of the still gases and may pass along the member 25 to rise at the apertures which carry the main currents of gas, and also to rise within the combined deflector and rarefaction member 13.

It will be understood that the number of ranks of vertical members may be varied in any desired way, the six ranks (3 to 8) being merely by way of illustration, while the number of members in each rank may also be varied. These variations may be conveniently carried out in a systematic way and according to definite plans, in providing separators suited to the volume and dust content condition of the gases to be handled. By substituting the member 11 for the member 12 and dispensing with the members 14, 17, and 18, in each rank, the width of the chamber may be reduced as may be desired in handling a smaller volume of gas. In a corresponding but inverse way additional members may be added to each of the ranks 3 to 8, in increasing the gas handling capacity of the separator, the number of ranks of members, of course, being decreased or increased as may be desired.

In situations where it may be desired to handle gases at temperatures above those to which iron or steel may successfully be subjected, I contemplate making the members and parts from heat resistant materials or metals. Usually steel may be expected to fail entirely or to have a short life at temperatures higher than 900 degrees Fahrenheit.

Therefore, in order to realize an operative separator for use in situations where the temperatures may be of the order mentioned, it is only necessary to substitute a suitable heat resistant material for ordinary metals in fabricating the separator equipment of my present invention.

While the various features of my invention are shown in what I believe to be a preferred embodiment, it will be understood that various changes in form and arrangement may be made without departing from the spirit of the invention or the scope of the appended claims.

What I claim is:

1. In a system for separating dust from gases, a chamber adapted to be traversed by a stream of dust-laden gases, means for intercepting the stream and establishing vortices in the gases having axial progression in the direction of gravity for concentrating the dust content, and diffuser means in the paths of said vortices for dissipating the vortical movements to separate the dust content.

2. In an apparatus for separating dust from gases, a chamber adapted to be traversed by a stream of dust-laden gases, means for divergently directing said stream to establish high and low pressure areas in the gases, and members for guiding gas flow from said high to said low pressure areas.

3. In a system for separating dust from gases, a chamber adapted to be traversed by a stream of dust-laden gases, deflector means in said chamber for divergently directing said stream to create low pressure areas on the rarefaction side of the deflector means, receptor means in the path of the divergently directed stream for intercepting the stream and establishing vortices in the gases to concentrate the dust content thereof, a dust receiving chamber for receiving the vortically moving gases, and diffuser means in said dust receiving chamber in the paths of said vortices for dissipating the vortical movements to separate the dust content, said dust receiving chamber communicating with said low pressure areas for flow of the dust-free gases thereto.

4. In a system for separating dust from gases, a chamber adapted to be traversed by a stream of dust-laden gases, rarefaction members and receptor members within said chamber, deflector members for directing said stream away from said rarefaction members to set up low pressure areas at the latter members while concentrating the stream at said receptor members to set up vortices in said gases, and members for dispersing said gases following their journey through said vortices and directing the gases to said low pressure areas.

5. In an apparatus for separating dust from gases, a chamber adapted to be traversed by a stream of dust-laden gases, a hop-

- per in association therewith, vertical deflector members forming a plurality of ranks in said chamber, rarefaction members in each rank for establishing areas of low pressure in said stream, receptor members in each rank for establishing vortices in the gases to concentrate the dust content hereof, and delivering the vortically moving gases into said hopper, and means in said hopper below each rank for dissipating the vortical movement and separating the dust content, said hopper communicating with said areas of low pressure for flow of the dust-free gases thereto.
6. In an apparatus for separating dust from gases, a gas flow chamber, a dust collecting chamber, receptor means in said flow chamber communicating with said dust collecting chamber for conducting a portion of the main gas flow thereto, deflector means for directing divergently the gases into said receptor means, whereby creating high and low pressure areas in said flow chamber, and gas return passageways leading from said dust collecting chamber are established to said low pressure areas.
7. In an apparatus for separating dust from gases, a gas flow chamber, ranks of elements comprising spaced receptor members and spaced deflector members inclined towards the receptor members to guide gas flow thereto, whereby a portion of the gases guided towards a given receptor member by the spaced deflector members in the preceding ranks enters the said receptor members and the other portion of the gases so guided passes between the spaced deflector members and between adjacent receptor members in the same rank, said deflector members being positioned to produce a sharp bend in the gases passing therebetween.
8. In an apparatus for separating dust from gases, a chamber adapted to be traversed by a stream of dust laden gases, spaced receptor members in the path of the stream for intercepting portions of the stream and establishing vortices in the intercepted portions having axial progression in the direction of gravity for concentrating the dust content of the intercepted portions, diffuser members for dissipating the vortical movement of said intercepted portions to separate the dust content thereof, and gas return passageways for return of the dust-free gases to the remainder of the stream.
9. In a system for separating dust from gases, a chamber adapted to be traversed by a stream of dust laden gases, deflector means for divergently directing said stream to establish high and low pressure areas, receptor members in the high pressure areas for intercepting the high pressure portions of the stream and establishing vortices in said portions having axial progression in the direction of gravity for concentrating the dust content of the said portions, and diffuser
- members in the paths of the vertical movements for dissipating the same.
10. In an apparatus for separating dust from gases, a chamber adapted to be traversed by a stream of dust-laden gases, means for establishing high and low pressure areas in the stream, spaced receptor members in the high pressure areas for intercepting portions of the stream and establishing vortices in the intercepted portions having axial progression in the direction of gravity for concentrating the dust content of the intercepted portions, a dust collecting chamber for receiving the vortically moving dust-laden gases, and diffuser members in said dust collecting chamber for dissipating the vortical movements to separate the dust, said dust collecting chamber communicating with said low pressure areas for flow of the dust-free gases thereto.
11. In an apparatus for separating dust from gases, a gas flow chamber, ranks of elements comprising a receptor and spaced deflector members inclined towards the receptor to guide gas flow thereto, whereby part of the gas flow is guided towards and enters the receptor, and the remainder of the gas flow passes between the spaced deflector members, said spaced deflector members being positioned to produce a sharp bend in the gases passing therebetween.
- In witness whereof I hereunto set my hand this 14th day of November, 1925.
- HUDSON H. BUBAR.
